UNITED STATES PATENT OFFICE.

PHILIP CARPELES, OF MILWAUKEE, WISCONSIN.

HAND-STRAP FOR TRUNKS.

SPECIFICATION forming part of Letters Patent No. 416,566, dated December 3, 1889.

Application filed July 24, 1889. Serial No. 318,525. (No model.)

To all whom it may concern:

Be it known that I, PHILIP CARPELES, of Milwaukee, in the county of Milwaukee, and in the State of Wisconsin, have invented certain new and useful Improvements in Hand-Straps for Trunks; and I do hereby declare that the following is a full, clear, and exact description thereof.

My invention relates to hand-straps and their attachment to trunks, &c., and will be fully described hereinafter.

In the drawings, Figure 1 is an elevation of my device, partly in section, on line 1 1, Fig. 2. Fig. 2 is a top view, partly in section, on line 2 2, Fig. 1; and Fig. 3 is a detail sectional view on line 3 3 of Fig. 1.

A is a portion of a trunk or chest.

B is the hand-strap, and C are metal re-enforces, one of which is slipped onto each end 20 of the strap. A tongue a is stamped out of each re-enforce during its formation, and after the re-enforce has been placed on the end of the strap this tongue is bent down into the slot b of the strap, as shown best in the 25 sectional portion of Fig. 2, and when the strap is in place it is secured by a clamp D, which is riveted to the trunk at c c c, and a lug d,

that is formed on the under side of the clamp and enters slot b, so that the strain incidental to handling the trunk is all brought on the 30 tongue a, which protects the strap and prevents the lug d from tearing it, while the slots permit of the usual sliding motion of the ends of the straps that allow the strap to lie flat against the body of the trunk when not in 35 use.

My device is simple and inexpensive and accomplishes a very useful object.

Having thus fully described my invention, what I claim as new, and desire to secure by 40 Letters Patent, is—

The combination, with a slotted hand-strap, of re-enforces each having a tongue entering the adjacent slot of the strap, and a clamp for each end of the strap having a lug for entering said slot to secure the strap in place. 45

In testimony that I claim the foregoing I have hereunto set my hand, at Milwaukee, in the county of Milwaukee and State of Wisconsin, in the presence of two witnesses.

PHILIP CARPELES.
